TIE LINING GUIDE MECHANISM

Victor M. Newman, New York, N. Y.

Application March 3, 1950, Serial No. 147,395

11 Claims. (Cl. 112—153)

1

This invention relates to necktie lining guide devices in a machine for making neckties.

The invention described herein may be used in necktie sewing machines such as illustrated and described in U. S. Patent Nos. 2,275,457 and 2,337,919. As set forth in said patents, the machines stitch the edges of a folded necktie fabric to the necktie lining. The disclosures of these patents were directed principally to means for guiding the lining as it was being advanced to the stitch forming mechanism together with the superposed fabric. The necessity and advantages for proper guidance were described and are generally obvious, it being highly desirable that the center of the lining be stitched to the edges of the necktie fabric by the machine.

As far as I am aware, machines of the type discussed herein have included relatively complex mechanism for insuring accurate guidance of the lining as it was fed to the stitching portion of the machine. Furthermore, such mechanism was arranged to accommodate a necktie lining of particular dimensions. In general, a slot was provided through which the lining was fed, and a cam or the like, which was constructed in conformity with the dimensions of the lining, served to effectively vary the size of the slot in accordance with the width of the lining as it was fed to the stitching apparatus. Other mechanism specifically adapted to the tie lining being served was also known in the art.

With the foregoing in mind, the present invention provides a guide which is of the utmost simplicity in accomplishing its required functions, i. e., that of guiding the travel of the lining so that it is in proper relationship with the necktie fabric when they jointly are fed to the stitch forming mechanism. The guide of the instant invention further automatically adapts itself to any shape of tie lining, notwithstanding various widths or configurations thereof. This is of importance in that it is not necessary to construct a different guide for each different lining. On the contrary, the lining itself determines the effective width of the slot through which it is fed and guided, which function was heretofore performed by auxiliary mechanism co-acting with the slot adjusting means.

The invention will be further understood from the following description and drawings in which:

Fig. 1 is an elevational view, partly broken away, of a necktie lining guide constructed according to the instant invention.

Fig. 2 is a cross-sectional view as taken along the lines 2—2 of Fig. 1.

2

Fig. 3 is a cross-sectional view as taken along the lines 3—3 of Fig. 1.

Fig. 4 is a view similar to Fig. 2 but illustrating a modified embodiment.

Fig. 5 is a view similar to Fig. 3, illustrating a corresponding portion of the modified embodiment of Fig. 4.

The guide mechanism of the instant invention is disposed in advance and in conjunction with a necktie sewing machine of the type shown in U. S. Patent No. 2,098,009. A flange 9 of the guide apparatus is secured to a support S so that top plate 10 is at the approximate level of the stitch forming mechanism. Thus, as a tie fabric T is fed across plate 10, it is sewn to the lining, as will be hereinafter described. In the form illustrated, the guide comprises front and rear walls 11 and 12 which are maintained spaced from each other by spacers 13 and are connected in such spaced relation by the nuts 14 and bolts 15. An open-ended horizontal slot 16 is formed in the walls 11 and 12.

Within the spacing, between the walls 11 and 12, and operating across the slot 16 is a guide rod 17 which has an eye 18 at one end thereof. Eye 18 is loosely supported around the shank 19 of bolt 20. Bolt 20 is disposed in a slot 21 formed through the walls 11 and 12, and nut 22 serves to tighten the bolt 20 in various positions of adjustment within slot 21. Guide rod 17 is thus swingably mounted for movement substantially vertically of or across the slot 16.

Guide rod 17 includes a center section which is of inverted V-shaped form, being open at the bottom and composed of the diverging legs 25 and 26. In the form illustrated, the legs 25 and 26 form an obtuse angle. The mounted end of rod 17 includes a rod section 27 which is substantially parallel with rod section or leg 25 while the leading or free end of the guide rod comprises a section 28 which is substantially parallel with the section or leg 26. Accordingly, the guide rod 17 is in the general form of a W. It will be noted, however, that the rod section 27 is inclined somewhat lower or more to the horizontal than rod section or leg 25.

The simple mechanism above described effectively guides a tie lining of any normally encountered dimensions. Referring to Fig. 1, the tie lining L is illustrated as having been inserted in slot 16 and between the triangle legs 25 and 26. The edges 27 and 28 of the tie lining act against the legs 25 and 26 so as to determine the vertical position of the guide rod 17. It is to be understood that the lining L tapers

throughout its length, being wide at its front portion and becoming narrower through its neck and rear portions. When it is interposed between the legs 25 and 26, it prevents the guide rod 17 from falling downwardly through the action of gravity and pursuant to its loose disposition on shank 19. In other words, the guide rod 17 is maintained in an elevated position to an extent depending upon the width of the lining L at that point thereof where it is disposed in the slot 16. Obviously, when the guide rod 17 is in an elevated position, as illustrated by the broken lines of Fig. 1, the distance between the legs 25 and 26 are much greater than when it is in a relatively lower position, as illustrated by the full lines of Fig. 1. In accordance with this principle of operation, one end of the tie lining is introduced below the upwardly directed leading leg or section 28 of the guide rod, and the lining is slipped into slot 16 between the triangle legs 25 and 26. Assuming now that the narrow end of the lining has been thus introduced, the guide rod 17 will be lifted, rotating slightly around shank 19, to an extent depending upon the width of the lining. It is desirable that the extreme free end of section 28 be of such a length that it is normally maintained above the lower edge 29 of slot 16 as by resting the leg 25 against bolt 30 when the guide rod 17 is at its lowest position, that is, when no lining is disposed between the legs 25 and 26. This condition, of course, causes the guide rod to fall into a normal rest position.

As the tie lining is transversely slid into place in slot 16 and is supported on the lower edges of the slot between the legs 25 and 26, the lining edges lift the rod 17 as hereinabove described. As the lining is drawn through the slot, the guide rod 17 rises or falls substantially vertically to an extent depending upon the width of the lining during its travel. During such rise or fall, the center of the lining is maintained substantially at a predetermined point as guided by the rising or falling triangular section. Thus, it will be observed that the legs 25 and 26, as they rise or fall above the lower edges of the slot 16, automatically adjust or vary the width of the slot in accordance with the width of the lining, a result that was heretofore accomplished by auxiliary mechanism.

Referring to Fig. 2, the necktie fabric T is illustrated as meeting the guided lining as they are directed toward the stitch forming mechanism. Generally, the fabric T is thus directed by hand while the lining is guided by mechanical means. Inasmuch as the guide device may be used with different machines, or, in any event, when the apex of the triangle or desired center is to be adjusted or varied, the nut 22 is loosened and the guide rod 17 is shifted horizontally in the slot 21 whereupon the nut 22 may be retightened. However, it has been determined that the bolt 20 may ride loosely in slot 21 if desired.

Figs. 4 and 5 illustrate extensions of the above described principle in that two spaced guide rods 35 and 36 are employed. Each of these guide rods duplicate guide rod 17, and they are respectively housed in vertical chambers formed by walls 37, 38 and 39. The purpose in employing two, spaced guide rods is to effect a more secure grip on the tie lining L as it is drawn through the slot. Each guide rod 35 and 36 actually rises or falls independently of the other inasmuch as they are disposed at spaced portions

of the necktie lining which may have slightly different widths.

It will further be evident that the central section comprising legs 25 and 26 may depart from the triangular form illustrated as long as it projects upwardly and can define or limit the effective width of the slot. Thus, the legs or sides of the projection may be arcuate, for example, forming together an arch which functions similarly. Whether the central section is of inverted V-form or whether it is arched, it is in any event concave, the extremities of the concavity guiding the lining as above described. Further, the rod may be mounted for true or precise vertical movement by supporting it in vertical slots at both ends of the rod, the lining being insertable through the slot 16.

What is claimed is:

1. Guiding mechanism for use in the fabrication of neckties comprising a wall having a horizontal slot formed therein, and a rod pivotally mounted on said wall and disposed adjacent to said slot, the pivot point of said rod being laterally disposed relative to said slot so that pivoting of said rod causes it to move substantially vertically of said slot, a central section of said rod being in V-form, the legs of which define and isolate a specific portion of said slot.

2. Guiding mechanism according to claim 1 and including a second wall maintained parallel to and spaced from the first named wall, said guide rod being mounted between said walls, the slot of said first named wall extending through said second wall.

3. Guiding mechanism according to claim 2 and wherein said guide rod is formed with an upwardly directed first leg, which is followed by said V-formed section, said upwardly directed leg normally extending above the lower edge of said slot when said rod is in its lowermost pivoted position.

4. Guiding mechanism for use in the fabrication of neckties comprising a body having a support for a necktie lining and over which the lining is adapted to be drawn lengthwise and a member mounted on said body adjacent to said support and mounted for substantially vertical movement above and relative to said support, said member having a substantially inverted V-shaped projection formed therein and movable above said support as said member moves, said projection being adapted to embrace the edges of a necktie lining as the lining is drawn past said support so as to guide the lining as it is thus drawn and whereby varying widths of said support appear between the legs of said inverted V-shaped projection as said projection moves above said support.

5. Guiding mechanism for use in the fabrication of neckties comprising a body having an open-ended horizontal slot formed therein for receiving a necktie lining, a rod movably mounted on said body for reciprocating movement substantially vertically across said slot and normally resting in a lowermost position relative to said slot, a section of said rod being in inverted V-form with the apex thereof uppermost, said V-form section rising or falling as said rod moves across said slot, the lower wall of said slot being adapted to support a necktie lining between the legs of said V-form section whereby said V-form section is restrained from falling to its normal or lowermost position to an extent depending upon the width of the lining between its legs.

6. Guiding mechanism for use in the fabrica-

tion of neckties comprising a body having a support for a necktie lining and over which support the lining is adapted to be drawn lengthwise and a pivoted rod having an upwardly projecting section of inverted V-form mounted on said body for substantially vertical movement relative and adjacent to said support as said rod pivots, so as to embrace the edges of the lining as it is drawn past said support and whereby varying widths of said support appear between the legs of said inverted V-form section.

7. Guiding mechanism for use in the fabrication of neckties comprising a body having a support for a necktie lining and over which support the lining is adapted to be drawn lengthwise preparatory to stitching it to a necktie fabric, and a rod pivotally mounted on said body and laterally of said support and having a section thereof in substantially inverted V-form, said section rising or falling adjacent to said support as said rod is pivoted so as to embrace the edges of the lining as it is drawn past said support, the apex of said section being upwardly directed whereby when said section falls a smaller width of said support appears between the legs of said V-form section and when its rises a greater width of said support appears between the legs of said V-form section.

8. Guiding mechanism for use in the fabrication of neckties comprising a pair of parallel vertical horizontally spaced apart walls having an open-ended horizontal slot formed therethrough for receiving a necktie lining, a rod pivotally mounted between said walls and laterally of said slot for rising and falling movement between said walls and transversely of said slot, a section of said rod being in V-form with the apex thereof uppermost and the legs extending downwardly, said V-form section rising or falling as said rod pivots transversely of said slot, the lower edges of said slot being adapted to support a necktie lining between the legs of said V-form section, said V-form section having a normal resting point at a lowermost position relative to said slot whereby the lining portion between said legs restrains said V-form section from falling to its normal or lowermost position to an extent depending upon the width of the lining portion, said rod having an initial upwardly directed leg

5
10

normally extending above the lower edges of said slots when said V-form section is in said lowermost position.

9. Guiding mechanism according to claim 8 and including a third parallel wall and a second rod substantially duplicating said first mentioned rod and pivotally mounted between the first mentioned two walls and said third wall for movement in a plane substantially parallel to the plane of movement of said first rod.

15
20
25

10. Guiding mechanism for use in the fabrication of neckties comprising a first member and a second member disposed side by side, a pivot pin connecting one of said members to the other member for affording pivotal movement in respect thereto, said first member being formed with a horizontal slot through which a necktie lining is adapted to be drawn, said second member being formed with a substantially inverted V-shaped section which reciprocates transversely of and adjacent to said slot during said pivotal movement, said V-shaped section being adapted to embrace the edges of the lining adjacent to said slot as the lining is drawn therethrough.

30
35
40

11. Guiding mechanism for use in the fabric of neckties comprising a first member and a second member disposed side by side, means for reciprocatingly moving said first member relative to said second member in a substantially vertical plane, one of said members being formed with a support over which a necktie lining of varying width is adapted to be drawn, the other member being formed concavely in a vertical plane, the concavity of which reciprocates vertically in respect to said support as said necktie lining is drawn thereover, the extremities of said concavely shaped member being adapted to embrace the edges of the necktie lining after leaving said support when the necktie lining is drawn thereover.
